UNITED STATES PATENT OFFICE.

JOHN P. SHEPPARD, OF SALEM, NEW JERSEY.

KNITTING-MACHINE.

No. 853,325.

Specification of Letters Patent.

Patented May 14, 1907.

Application filed January 31, 1906. Serial No. 298,740.

To all whom it may concern:

Be it known that I, JOHN P. SHEPPARD, of the city and county of Salem, State of New Jersey, have invented an Improvement in Knitting-Machines, of which the following is a specification.

My invention has reference to knitting machines and consists of certain improvements which are fully set forth in the following specification and shown in the accompanying drawings which form a part thereof:

The object of my invention is to provide a knitting machine with capacity for knitting a stocking with open or lace work entirely around the leg portion and down the instep portion and with solid or regular knit heel, sole and toe portion.

It has been customary in knitted hose to form a stocking of a single thread with the lace or open work upon the front of the leg and instep portions and with regular knit back of the leg, heel, sole and toe portions but great difficulty has been experienced in producing such a stocking with the lace work or open work all around the leg portion and the entire stocking made seamless and at one continuous operation. My invention overcomes this difficulty in a simple and inexpensive way, and is adapted for use in connection with ordinary knitting machines found on the market and heretofore adapted to produce tuck work and plain knitting and open work by removal of needles; and more specifically my invention is adapted to knitting machines employing beard needles having reciprocating motion such for example as set forth in the U. S. Letters Patent to E. J. Franck, No. 536,616 of April 2, 1895, No. 656,538 of August 21st, 1900 and No. 671,995 of April 16th, 1901 and No. 706,509 of August 12th, 1902 to Bard, and to which reference is made for the general details and mode of operation of the machine. It will be sufficient, in describing my improvements, to assume certain operations for the ordinary and well known parts of the machines as disclosed in said Franck and Bard patents.

My invention consists in providing for cooperation with some of the needles, constituting two sets, of a series of pads or cams which are adapted to close the beards of the needles to prevent them taking the thread when it is desired to make a miss-stitch or open work and without removing any of the needles, and in which the cams or pads for the set of needles which knit the front of the

stocking may be operated independently of the pads or cams for the needles which knit the rear part of the stocking, heel, sole and toe, combined with pattern-controlled mechanism for independently operating the pads or cams of the set of needles for knitting the front of the stocking or for operating all of the pads or cams for the needles of both sets at will, whereby lace work or open work may be produced upon one-half of the needles only or upon all of the needles as desired during one continuous operation of knitting a stocking.

In the operation of my invention, the tubular knitted fabric may produce a stocking in which the upper part of the leg portion may be of solid or plain knit fabric, the lower part of the leg portion with lace work all around, the foot formed with solid sole, heel and toe and lace instep and with the toe end of the instep made of plain knit fabric to more easily close the toe by looping, thereby producing a most perfect stocking of any desired pattern.

My invention also comprehends details of construction which, together with the features above specified, will be better understood by reference to the drawings, in which:

Figure 1 is a plan view of sinker bed and sinkers and pattern mechanism for operating the cams or pads for the needles; Fig. 2 is a vertical section through the needle head and operating mechanism; Fig. 3 is a perspective view of the pivoted cam for operating the pads; Fig. 4 is an elevation of same; Figs. 5 and 6 are perspective views of sinkers and pads suitable for use in my invention for the front and back sets of needles; Fig. 7 is a plan view of one of the sinkers and pads; Fig. 8 is a plan view of a series of sinkers and pads; Figs. 9 and 10 and 11 are plan views of links adapted to be used in the pattern chain for controlling the pads; Fig. 12 is a side elevation of the knitting head and tuck mechanism; Fig. 13 is a sectional plan view of the same; and Fig. 14 is an elevation of the cam ring for the tuck sinkers.

B is the needle head and is stationary.

F are the needles which are of the bearded type. These needles are arranged in two sets, each approximately extending half around the needle cylinder. Each set is reciprocated by one of the lifter frames C C' and they are reciprocated alternately in the well known manner. One of these sets of

needles is further under control of fashioning devices for throwing needles into or out of action for forming the heel and toe but the details of that mechanism are not shown.

5 D' is the sinker bed and is carried by the needle head B and D is the sinker gear, rotating upon the sinker bed and having cam grooves for reciprocating the sinkers E away from the needle shanks when the thread 70 guide is in the act of delivering the thread.

R is the thread guide and rotates with the sinker gear.

The foregoing parts are all well known and will not need any further description.

15 As pointed out, the needles are arranged in two halves and reciprocated alternately, and the sinkers are arranged in an annular form about the needle head and the sinkers E of the needles F which knit the front half of the 20 stocking may be provided with pads E' having upwardly extended shoulders of considerable height, while the needles F which knit the rear half of the stocking are provided with pads E² having similar upwardly extending shoulders but of less height. These 25 pads may be attached to the sinkers in any convenient manner and are adapted, when moved toward the needles, to present their cam portions e to the beards of the down- 30 wardly moving needles for the purpose of closing the beards of the said needles and preventing the thread passing under beards thereof, the result being that the needle fails to knit and openwork or miss-stitches result. 35 This open work when combined with tuck stitches produce lace work effects. The tuck effects may be produced upon a portion only of the needles in any well known manner, as for example, by the means set out in 40 the U. S. Patent to Bard No. 706,509 dated Aug. 12, 1902.

The tuck mechanism is more fully shown in Figs. 12, 13 and 14 in which f are the stationary jacks arranged radially in respect to the needle cylinder and below the sinker bed. 45 The jacks for such needles as are to produce tuck stitches by having their beards open when descending are shown at f² and are pivoted so as to rock under the influence of the 50 semi-circular cam rings g'. These segments or semi-circular cam rings g' are provided with oblique cam slots g² which work on pins g³ and are rocked by pins g⁴ with the result of causing the cam ring segments to rise or fall, 55 which acting on the heels of the jacks f², cause them to oscillate. The pins g⁴ are operated by the pattern mechanism R' which by rods r r', levers R² R³ and pattern chain R⁴ controls the time of action of the jacks f², 60 in being withdrawn from the needles to prevent them shedding their loops. This mechanism is fully disclosed in detail in the aforesaid Letters Patent No. 706,509 to Bard and may be taken as an example of suitable tuck 65 mechanism adapted for use with my inven-

tion. Any other suitable tuck mechanism may be employed in lieu thereof.

In practice, I arrange pads or cams to act upon certain needles so as to produce the open work to a greater or less degree in combination with said tuck work to produce the lace work. Of course, it is evident that open work alone may be produced if the tuck work is omitted. I do not confine myself to any arrangement of pads as they may be arranged to operate upon isolated needles or upon needles in sets of two or more as desired.

The pads are operated by a pivoted cam P having the two operating cam faces P' and 80 P², the former acting upon all of the pads to move them toward the needles and the latter acting only upon the pads E' which are employed in connection with those needles which knit the front only of the leg of the 85 stocking. The cam P is pivoted at p at its middle to the cam ring or gear D of the sinker bed which operates the sinkers during its rotation. By being oscillated in one direction, the cam surface P' of this pivoted cam comes 90 into position to move all of the pads of both sets of needles. When the cam P is oscillated in the other direction, the other cam surface P² comes into position to operate only the pads E' of the set of needles which knit the front of the stocking and instep. The cam surface P² has an undercut portion which permits the free passage of pads E' 95 for the needles which knit the back half of the stocking without moving said pads.

The pivoted cam P is moved by a bar G guided in a guide G² on the cam ring or sinker gear D and this bar is provided with an upwardly extending pin carrying a roller g by which the bar is moved.

H is a lever having the cam surfaces h and h' with a slot between them through which the roller g of the bar G travels; and by means of the cam faces h or h' said bar is shifted inward or outward with corresponding oscillation of the pivoted cam P. The lever H is pivoted upon a standard H' and is reciprocated by rod J², chain lever J pivoted at J', and pattern chain I at the distant end of the knitting machine. The chain links are provided with lugs I' and I² for shifting the chain lever J and thereby throwing the cam faces h or h' of the lever H into operating position; and said chain may also be provided with links having cam faces I⁴ for holding the cam lever H in central position when none of the pads are to be operated by the cam P.

It will now be understood that when the pivoted lever J is in intermediate or central position, neither of the cam faces h or h' position the cam P to operate the sinker pads and consequently, in that position, the knitting would be plain or simple tuck work if the machine were operated to produce tuck 130

stitches; but if the cam face *h* is put into operating position, then open work is produced at intervals all around the leg of the stocking and which, with the tuck work, forms lace work, or lace work and open work combined; and, if the other cam face *h'* of the cam can be put into operative position, then the open work ceases to be formed upon the rear half of the needles, and the back of the stocking, the heel, sole and toe may then be formed of plain knit fabric while the instep portion is knit upon the other half of the needles with lace work or openwork, as desired. After the completion of the sole and instep portions down to almost the end of the instep, the cam faces *h* and *h'* are thrown to the intermediate position so that all of the needles of both sets knit plain or solid fabric. This enables the solid fabric of the instep to be perfectly looped to the solid fabric of the toe to make a perfect seam or closure. It is also evident that this machine has the capacity of knitting plain work, tuck work, open work, or lace work at will, so that a great variation in design may be given to the stocking. For example, the lace work may be formed only around the ankle part and instep portion, or only on the front of the leg portion, or only on the instep and front of the ankle, or all around the whole or any part of the leg portion and on the front of the ankle and instep portion. It will be evident that where the stocking is to have lace work all the way down the front of the stocking, the sinker pads *E'* may be omitted and the needles upon each side of the tuck needles removed. This however has the disadvantage that the end of the instep portion will not terminate in solid fabric for perfect looping with the toe. It is also undesirable, because the upper part of the leg portion could not be knit solid at the front.

Where two adjacent needles are required to produce miss-stitch or openwork I may provide the pad cams upon each side of the sinker as shown at *E'* Fig. 8, or a single pad may be upon the sinker.

The pad cams are arranged between the sinkers and in line with the needles or such of them as are to be operated to make open work. As shown in the drawing these pad cams are carried by the sinker bed through the sinkers, but it is immaterial how they are supported as they may be independent of the sinkers, as for example as set out in Letters Patent No. 824,043 of June 19, 1906 granted to J. P. Sheppard, *et al.* Ordinarily there is sufficient movement possible to the sinkers in their cams to permit the desired manipulation of the pad cams, but it is evident that these pad cams may if desired have their shanks extended outward sufficiently to be directly supported by the sinker bed, in which case they would be as illustrated with the nose of the sinker part removed, that is

so as to terminate at the cam part *e*. Pad cams of this nature are well known and need no further description.

It is evident that the upwardly extending shoulders of the pads which are actuated by the cam surfaces may be on the sinkers when the pads are attached to the sinkers, or otherwise, and it is also evident that it is immaterial how the cam faces coöperate with the pads or sinkers as long as one set or both sets of the said pads are adapted to be operated by said cam mechanism. I do not confine myself to any particular operating means for moving the pads, as such means may be made in various ways without departing from the spirit of the invention, which comprehends broadly, the pads for the front and rear sets of needles combined with means for operating all of the pads or those only of the front needles under the control of pattern mechanism.

My invention is more particularly an improvement of the knitting machine set out in the aforesaid Letters Patent No. 824,043 of 1906, and while I have shown my invention as applied to the "Franck" and "Bard" types of knitting machines I do not restrict myself to any particular make of this class of machines, as my invention is applicable to all forms of knitting machines employing vertically reciprocating beard needles, sinkers, and means for producing tuck work thereon.

I do not confine myself to the details of construction as these may be modified in various ways without departing from the spirit of my invention.

Having now described my invention what I claim as new and desire to secure by Letters Patent, is:

1. In a knitting machine the combination of front and rear sets of reciprocating beard needles, pads for part of the front needles, pads for part of the rear needles, and pattern controlled devices comprising means to operate at one time only the pads of the front needles and at another time the pads of both the front and rear sets of needles.

2. In a knitting machine the combination of front and rear sets of reciprocating beard needles, pads for part of the front needles, pads for part of the rear needles, cam devices comprising means to operate at one time only the pads of the front needles and at another time the pads of both the front and rear set of needles, and pattern mechanism for controlling said cam devices to cause the open work to be produced only by the front set of needles or by both the front and rear sets of needles at will.

3. In a knitting machine the combination of front and rear sets of reciprocating beard needles, pads for part of the front needles, pads for part of the rear needles, devices constructed to operate at one time only the pads

of the front needles and at another time the pads of both the front and rear sets of needles consisting of a movable cam having two operating portions respectively adapted to operate only one or both of the sets of pads, shifting devices for the movable cam to bring either of its operating portions into operating position alternately, and pattern mechanism for controlling the shifting devices, whereby one or both sets of pads are caused to be shifted.

4. In a knitting machine, the combination of reciprocating beard needles, two sets of pads for a portion of said needles to cause them to make open or miss-stitch work in different portions of the knitted fabric, means whereby only one set of pads may be moved into operative position, pattern mechanism to cause said means to move both sets of said pads into operative position at will, whereby open work may be made by one set of needles only at one place in the fabric and by both sets of needles at another place in the fabric.

5. In a knitting machine, the combination of reciprocating beard needles, two sets of pads for a portion only of said needles to cause them to make open or miss-stitch work, means whereby only one set of pads may be moved into operative position, means whereby both sets of pads may be moved into operative position, and pattern mechanism to control the operation of said means whereby either one set or both sets of pads are moved into operative position and definite patterns of open or lace work thus produced at specific places on the stocking.

6. In a knitting machine, the combination of reciprocating beard needles, sinkers for said needles, two sets of sinker pads for said needles one set having high shoulders for one-half of the needles and the other set having low shoulders for the other half or set of the needles, and cam mechanism for operating upon the sinker pads for operating one or both sets as desired.

7. In a knitting machine, the combination of reciprocating beard needles, sinkers for said needles, two sets of sinker pads for said needles one set having high shoulders for one-half of the needles and the other set having low shoulders for the other half of the needles, and pattern controlled cam mech-

anism for operating upon the sinker pads for operating one or both sets as desired.

8. In a knitting machine, the combination of reciprocating beard needles, sinkers for said needles, two sets of sinker pads for said needles one set having high shoulders for one-half of the needles and the other set having low shoulders for the other half of the needles, and cam mechanism for operating upon the sinker pads for operating one or both sets as desired consisting of the pivoted cam P having operating face P¹ to operate upon all of the sinker pads and face P² to operate only on the high shouldered pads, and pattern controlled mechanism for shifting the pivoted cam.

9. In a knitting machine of the class described, a needle cylinder, two sets of beard needles for said cylinder, means for reciprocating said sets of needles alternately, means for feeding a thread to the needles, and means for producing tuck stitches upon a portion of the needles of each set, combined with pattern controlled devices for automatically causing the open work to be produced upon a portion of the needles of one or both sets of needles, whereby lace effects may be produced part way or wholly around the stocking.

10. In a machine of the class described, a needle cylinder, two sets of beard needles, means for reciprocating the said sets of needles alternately, means for knitting a heel and toe upon one set of the needles, means for producing plain or tuck stitches upon a portion of the needles of each set, combined with pads for a portion of the needles of each set for rendering said needles inoperative so as to make open work, cam devices for operating the pads of one set of the needles, cam devices for operating the pads of both sets of needles, and pattern mechanism for putting either of the cam devices into operative position at will whereby lace work may be made upon one set or upon both sets of the needles as dictated by the pattern mechanism.

In testimony of which invention, I have hereunto set my hand

JNO. P. SHEPPARD.
